UNITED STATES PATENT OFFICE.

WILLIAM ALBERT BABER, OF WICHITA FALLS, TEXAS.

ROLLER-SHADE FIXTURE.

Application filed December 31, 1925. Serial No. 78,626.

This invention relates to a fixture designed for use in connection with roller shades, maps and other devices adapted to be rolled and unrolled relative to a wood roller or the like.

It is an object of the invention to provide a supporting bracket which can be used at either end of the roller and which has a means combined therewith whereby a cord can be utilized for rotating the roller in either direction either to wind or unwind the shade or the like thereon.

Heretofore shade rollers and the like have been provided with pulleys on which cords have been mounted, the cords being held to the pulleys by suitable means to produce sufficient friction to insure rotation of the roller. Such means, however, have not been reversible so as to be used at either end of the roller.

It is an object of the present invention to provide such a means which can be used at either end of the roller, which is simple in construction and which can be applied readily.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is a front elevation showing the present invention applied to a shade roller, a portion of the roller and shade being broken away.

Figure 2 is a top plan view of the structure shown in Figure 1.

Figure 3 is an end elevation of the bracket constituting the present invention.

Figure 4 is a section on line 4—4 Figure 3.

Figure 5 is a view similar to Figure 3 but showing a modified construction.

Referring to the figures by characters of reference 1 designates a balanced roller on which a shade 2 or the like can be mounted. This roller is provided, as ordinarily, with bearing pins 3 extending from the ends

thereof, the outer end portions of the pins 55 being angular in cross section as indicated at 4. A bracket 5 of ordinary construction is adapted to engage and support one of these pins. The other pin is adapted to be supported by a special form of bracket which 60 constitutes the present invention. This bracket includes an attaching base or plate 6 provided with fastening screws 7 or the like and from one side of which extends an arm 8 formed with a disk-like terminal 9 in 65 which is provided an opening 10 constituting a bearing for the pin 3 as shown in Figure 4. A pulley 11 is fitted tightly on the angular portion of the pin 3 so as to rotate therewith and this pulley is provided with a 70 marginal groove 12 in which is seated an operating cord 13. The cord is held within the groove of the pulley by guard fingers 14 which are integral with the disk 9 and lap the periphery of the pulley 11 at diametrically opposed points as shown particularly in Figure 3. A sleeve 15 is integral with the base 6 and seated therein is one end of a spring 16 the other end of which is arcuate 75 as shown at 17 to constitute a resilient shoe 80 adapted to bear upon the cord 13 at points between the fingers 14. This shoe exerts sufficient pressure on the cord to insure rotation of the pulley 11 when the cord is pulled in either direction. Obviously when 85 one part of the cord is pulled the pulley will be rotated in one direction whereas when the other portion of the cord is pulled the pulley will be rotated in the opposite direction.

When it is desired to use this fixture at the other end of the roller, the fixture is inverted, the spring 16 is pulled out of the sleeve 15 and inserted in the other end thereof and the cord is reversed on the pulley.

Instead of having a removable shoe held in place frictionally as shown in Figures 3 and 4, the arm 8' can be provided with integral extensions 18 located adjacent diametrically opposed portions in the pulley 19. These extensions can be formed integral with the arm 8' and can be provided with opposed integral shoes 20. One of these shoes will always be uppermost and this uppermost shoe is the one which will engage the cord 21 and press it upon the pulley 19 so as to insure rotation of the pulley.

ley when the cord is actuated. By reversing the fixture shown in Figure 5 the cord will be positioned under the other shoe 20.

What is claimed is:

- 5 1. A bracket for supporting one end portion of a shade roller, including an attaching base, an arm extending therefrom, a pulley adapted to engage the bearing pin of a roller and having a marginal groove, said bracket being reversible with either of two opposed portions of the pulley uppermost, and resilient means carried by the bracket adapted to press an operating cord upon the uppermost portion of the pulley when 15 the bracket is in either of its two positions.
2. A reversible supporting bracket for a shade roller including an attaching base, an arm extending therefrom having an opening adapted to receive the bearing pin of 20 a roller said arm being invertible for use at either end of the roller, a pulley adapted to engage and rotate with said bearing pin and having a peripheral groove adapted to receive a depending operating cord, means 25 extending from the arm adjacent diametrically opposed portions of the pulley adapted to hold an operating cord within the groove,

and yielding means adapted to engage the operating cord midway between said holding means to press the cord downwardly 30 against the pulley when the bracket is in use at either end of the roller.

3. A reversible supporting bracket for a shade roller including an attaching base, an arm extending therefrom having an opening adapted to receive the bearing pin of a roller, said arm being invertible for use at either end of the roller, a pulley for engaging and rotating with the pin having a peripheral groove adapted to receive a depending operating cord, means extending from the arm at diametrically opposed portions of the pulley adapted to hold an operating cord within the groove, and diametrically opposed friction shoes carried by said 45 means adapted to engage the top portion of the cord seated in the groove when the arm is in either of the two positions to which it is inverted.

In testimony that I claim the foregoing 50 as my own, I have hereunto affixed my signature.

WILLIAM ALBERT BABER.
